UNITED STATES PATENT OFFICE.

EDWARD WETTERHAHN, OF GRANADA PARK, CALIFORNIA.

CARBURETER.

1,155,457.

Specification of Letters Patent.

Patented Oct. 5, 1915.

Application filed September 23, 1914. Serial No. 863,118.

To all whom it may concern:

Be it known that I, EDWARD WETTERHAHN, a citizen of the United States, residing at Granada Park, in the county of 5 Los Angeles and State of California, have invented certain new and useful Improvements in Carbureters, of which the following is a specification.

This invention relates to improvements in carbureters for internal combustion engines for burning a low grade fuel oil as well as gasolene; and the objects of my improvements are, first, to provide a double adjustment for the fuel oil feeding valve, manually and automatically, by having a flattened pin turning inside of double tubes, which are provided with holes, normally to fit above each other, but as one of the tubes may be set or adjusted manually, the holes 10 in that adjusted tube will shift over the spaces left between the holes of the stationary tube, thus the openings for the fuel feeding may be set to suit the fuel and requirements of the engine, and besides this, 15 the turning pin, being connected with the throttle by levers, may thus be turned inside of the inner tube, closing or opening gradually the openings of the inner tube; second, to provide an air-inlet throttle, 20 which is connected with the gas-throttle by a spring outside of the carbureter, adapted to decrease the tension of the spring of the air-inlet throttle when opening the gas-throttle, thus giving freely air by increasing 25 gas-feeding; and, third, to provide a priming tube to the carbureter with a hollow stem in the valve of the priming tank, adapted to allow enough fuel oil to enter 30 the priming tube on the carbureter, and also 35 adapted to allow the fuel oil, which thus entered the priming tube on the carbureter, to flow into the carbureter after the valve in the priming tank has been closed, thus operating the engine on this good fuel oil until 40 the low grade fuel oil is in a condition to 45 explode to operate the engine.

I attain these objects by the mechanism illustrated in the accompanying drawing, in which—

50 Figure 1 is an assembly of my devices on a carbureter. Fig. 2 is a horizontal sec-

tional view on line *a—a* in bigger scale, of my fuel oil operating valve. Fig. 3 is a section through the spray on line *b—b* of Fig. 2. Fig. 4 is the same, where the spray 55 holes are reduced appearing almost closed by turning one of the tubes. Fig. 5 is my check valve on my carbureter. Fig. 6 is my shut off valve in my priming tank. Fig. 7 is the upper end of my shut off valve. 60

Similar figures refer to similar parts throughout the several views.

At a suitable distance from the top of the casing 1, see Fig. 1, is in the usual manner a gas throttle 2, which will be operated 65 in the usual manner by a lever 3. Pivotaly connected to throttle-lever 3, by connecting rod 4, is the fuel oil operating lever 5 on a shaft 6, which is the fuel oil controlling valve, shown in Fig. 2 in a bigger scale. 70 One end of the fuel oil operating valve is cut down on one side, as indicated at 7, the purpose and function of which will be later described. Spray tube 8 is slidingly fitted in spray adjusting tube 9, which may be set 75 by lever 11 to give full opening of the spray holes 10, as indicated in Fig. 3, or spray adjusting tube 9 may be turned by lever 11 to reduce the spray holes 10 as indicated at Fig. 4. The fuel oil coming in at 12, see 80 Fig. 1, until the float 13 is lifted up in the usual way, closing at its highest point in the usual manner the inlet as indicated at 14. From the float chamber 15, the fuel oil will flow through the bore 16, thence 85 through the bore 17, further, see Fig. 2, through bore 18 and then through bore 19 into the spray tube 8. The spray tube 8 may be soldered into the arm 20, which will fit on the other end over the lug 21, 90 where it may be held tight by the screw cap 22. After the fuel oil enters the spray tube 8, the suction of the engine will take it up through the openings 10, whether these are full opened as indicated in Fig. 3, or 95 reduced to a small spray as indicated at Fig. 4. In either position, full opened or reduced, the outcoming spray may also be regulated in addition to this setting of the spray adjusting tube 9, by the fuel oil controlling valve 6, which is operated by the throttle lever 3, through the 100

connecting rod 4, see Fig. 1. In turning the fuel oil controlling valve 6, the flat cut end, as indicated at 7, see Figs. 3 and 4, will give a free passage to more or less of the spray holes 10, thus adjusting the spray of the fuel oil mechanically, in any of the positions set manually by the lever 11. At 22^a see Fig. 1, a hot air tube may be connected, which is normally shut off by the air valve 23, turning on a shaft 24. An air valve lever 25 secured to shaft 24 may be connected by a coil spring 26 with a connecting lever 27, secured to the throttle-shaft 2, thus, when turning the throttle lever 3, decreasing the tension of the spring 26, which will allow the hot air to enter the carbureter easier in proportion to the increasing opening of the fuel oil spray 10, while, when starting the engine, the air valve 23 may be kept tight by the coil spring 26 and a little cold air may enter the carbureter at the lower end as indicated at 28, though the coil spring is not so strong to prevent an automatic movement of the air valve for the hot air to enter the carbureter after the engine may be started by the priming fuel oil. The connecting lever 27, secured to the shaft of the throttle 2, being shown as turning in the left hand direction when opening the throttle, is relieving the spring 26, connected to the lever 25 of the air valve 23, while on the other side of the throttle 2, the throttle lever 3 is connected by the rod 4 to the lever 5; thus, when 35 opening and operating the carbureter by the lever 3, simultaneously opening the throttle, the spray holes and the air valve.

For starting the engine, when using a low grade fuel oil, a priming tube 29 is provided 40 for furnishing a good fuel oil from a priming tank 30. Secured directly on the carbureter is a check valve 31, which will not allow the back fire of the engine to enter the priming tube 29. The other end of the 45 priming tube is normally shut off from the priming tank by the valve stem 32, which is hollow see Fig. 6 and as it has a small hole 33 on its upper end, see Fig. 7, all fuel oil having entered the priming tube 29, can be 50 sucked by the engine, furnishing the engine with good fuel oil for a suitable time to allow the low grade fuel oil to become explosive. The check valve, see Fig. 5, previously referred to, comprising a casing 34, 55 into which a spring 35 and a ball 36 may be inserted and held in this position by a tight fit bushing 37. The shut off valve for the priming tank, shown in Fig. 6, is secured on the bottom of the priming tank 30 by the 60 lock nut 38. The hollow stem 32 is shown in closing position. Fuel oil from the priming tank will have to go through the holes 39, which are covered by screen 40 to keep the priming oil clean, downwardly through the

bore 41, which is possible only when the 65 hollow stem 32 is lifted up above the holes 39. The hollow stem 32, see Fig. 7, is lifted up by turning the lever 42, hereby shifting the pin 43, which is secured to the lever, upwardly along the inclined edge of the bushing 44, which is secured to the priming tank 30. The priming fuel oil will enter the priming tube through the holes 39, see Fig. 1 and Fig. 6, then the lever 42, see Fig. 7, may be turned back again, shutting off the 75 fuel oil in the priming tank, but as the hollow stem 32 has a small opening 33 on its top end, all fuel oil in the priming tube 29 may be sucked into the engine, giving a suitable time to allow the low grade fuel 80 oil to become explosive. The hollow stem 32 is pressed down as soon as the lever 42 is turned back to the position shown in Fig. 7, by the spring 45, which is placed between the top of the priming tank 30 and a sleeve 85 46, which may be secured upon the hollow stem 32.

Having thus described my invention, I claim:

1. In a carbureter, a spray tube having 90 spray holes, a float chamber communicating with the spray tube, a spray adjusting tube upon the spray tube having holes normally to fit above the spray holes of the spray tube, a lever for manually adjusting the 95 spray through the spray holes by the spray adjusting tube, a fuel oil controlling valve having one end cut down for a fuel oil passage inside of the spray tube, a fuel oil operating lever attached to the fuel oil controlling valve, a throttle above the spray tube, a lever attached to the throttle connected by a rod with the operating lever of the fuel oil controlling valve, adapted for mechanically operating the fuel oil controlling valve with the throttle, and an air valve having a lever connected to another lever on the gas throttle shaft by a spring adapted to decrease the tension of the spring when 100 opening the throttle. 110

2. In a carbureter, for burning a low grade fuel oil, a spray tube having spray holes, a float chamber communicating with the spray tube, a spray adjusting tube upon the spray tube having holes normally to fit above the spray holes of the spray tube, a lever for manually adjusting the spray through the spray holes by the spray adjusting tube, a fuel oil controlling valve having one end cut down for a fuel oil passage inside of the spray tube, a fuel oil operating lever attached to the fuel oil controlling valve, a throttle above the spray tube, a lever attached to the throttle connected by a rod with the operating lever of the fuel oil 115 controlling valve, adapted for mechanically operating the fuel oil controlling valve with the throttle, another lever attached to the 120

throttle on the other side, a spring attached to this lever, an air valve having a lever connected to the spring adapted to decrease the tension of the spring when opening the 5 throttle, and a priming tube having a valve with a hollow stem shutting off the priming oil allowing the priming oil in the priming tube to be sucked into the engine while the

low grade fuel oil in the carbureter is getting warmed.

In testimony whereof I hereunto affix my signature in the presence of two witnesses.

EDWARD WETTERHAHN.
